UNITED STATES PATENT OFFICE.

OTTO SIEFERT, OF BERLIN, GERMANY.

LIQUID-FUEL-SUPPLY DEVICE FOR INTERNAL-COMBUSTION OR LIKE ENGINES.

Application filed May 2, 1924. Serial No. 710,680.

To all whom it may concern:

Be it known that I, OTTO SIEFERT, a citizen of the Republic of Germany, residing in Berlin, Germany, have invented certain new

5 and useful Improvements in Liquid-Fuel-Supply Devices for Internal-Combustion or like Engines, of which the following is a specification.

This invention comprises improvements in 10 or relating to liquid fuel supply devices for internal combustion or like engines and more particularly to double acting liquid fuel supply devices in which the fuel is drawn by suction from a main tank and from which 15 it passes on its way to the carburettor through a supplementary tank provided with means for controlling the connections between said main tank and carburettor and for connecting the supply device alternately 20 to the suction source and to the atmosphere. Known fuel supply devices of this type are provided with two adjacently arranged suction chambers, with a float in each chamber, each of said floats controlling a suction and 25 an air valve respectively. The openings for the fuel inlet and discharge are controlled by automatic valves. As long as the chambers are subjected to suction, fuel is sucked in; and as long as they are connected to the 30 atmosphere, fuel is delivered to the supply pipe of the carburettor.

The device according to this invention differs from such known double-acting fuel supply devices, in that two suction chambers 35 are adapted to be connected alternately to a source of suction and to the atmosphere and in that the air and suction valves in both chambers are both controlled by one float only, so that the working gear is simplified 40 whereby the working of the device is made more reliable.

For example, a simple construction of the fuel supply device may be formed by the suction chambers being arranged concentri- 45 cally or one within the other, and such a suction device is illustrated, by way of example, in the accompanying drawings, in which—

Fig. 1 is vertical section through the de- 50 vice, showing the float in its lowest position, and in which the inner chamber is connected to the suction source and is filled, whilst the outer chamber is subjected to atmospheric pressure and is discharging.

55 Fig. 2 shows the upper part of the device shown in Fig. 1, with the float at its highest

position. In this position of the parts the outer chamber will be filling during the discharge of the contents of the inner chamber.

60

Fig. 3 is a section through the fuel inlet in a different vertical plane to that shown in Figures 1 and 2.

The outer chamber 1 and the inner chamber 2 are connected at their top edges by a 65 ring 3, serving at the same time as a flange for securing the cover 4. The connection between the ring and cover is made airtight by means of a gasket 5. The cover is pro- 70 vided with connecting nipple 6 for the suc- 75 tion pipe, and a connecting nipple 7 for the fuel supply pipe, and contains the valves for connecting the chambers alternately to the suction pipe and to the atmosphere. The suction valve 8 for the outer chamber and 80 the suction valve 9 for the inner chamber 85 form a connected double-seated valve having between them a common valve-chamber 10 with which the suction passage 11 com- 90 municates.

On the double valve 8, 9 being lifted (Fig. 2) the valve chamber 10 is connected by means of the channel 12 to the outer chamber 1, by the upper valve 8 being raised from its rest but is closed to the inner chamber 2 by the lower valve 9. On the double 95 valve being lowered (Fig. 1) the outer chamber 1 is cut off from the valve chamber 10, while the inner chamber 2 is connected thereto by means of the passages 13 in the tubular 100 part which acts as a valve guide.

The connection of the two chambers 1 and 2 with the atmosphere or their isolation therefrom is controlled by a similar air valve 14. The latter is formed as a hollow 105 piston valve provided laterally with inclined passages 15, which effect, when the valve is lifted, (Fig. 2), a connection between the inner suction chamber 2 and the valve cham- 110 ber 16 in which the piston valve works, this chamber being connected to the atmosphere by the passage 17, and to the outer chamber by a second passage 18. The passage 18 is closed to the atmosphere when the air valve 14 is lifted (Fig. 2) (while air is admitted to the chamber 2) and opened when the valve 14 is closed (Fig. 1) (while air is cut off from the inner chamber 2). Thus the valve 14 serves simultaneously as a control valve for the two chambers.

The double seated valves 8 and 9 as well as the slide valve 14 are connected by a plate

or bridge 19, mounted on a vertical tube 20 which is guided on a pin 21 secured in the cover 4. A float 22 is guided on the tube 20 and its movements are limited by a flange 23 on the tube 21 and a flange or projection on the bridge 19.

5 A second smaller float 24 is arranged in the outer chamber 1 and has a stem which is guided in a spider 25 or the like secured 10 to the underside of the flange ring 3. A valve 26 on the float stem serves for closing the passage 12 when the outer chamber 1 becomes fully charged.

The fuel supply to the inner chamber 2 15 takes place through a passage 27 and to the outer chamber 1 through a passage 28 in the cover 4 (Fig. 3). The ends of these passages are closed by flap valves 29 and 30 which are automatically opened by the flow 20 of the fuel.

The discharge of the fuel from the inner chamber 2 takes place through a tube 31 which passes through the bottom of the outer chamber 1, and is provided with an 25 automatic check valve 32.

A similar valve 33 is provided in the bottom of the outer chamber 1. Both valves are housed in a casing 34 provided with a socket 35 for the tube leading to the carburettor.

30 The operation of the fuel supply device according to this invention is as follows:—

Assuming the inner chamber 2 is empty and the outer chamber 1 is full, the float will be at its lowest position (Fig. 1). The 35 suction valve 9 is open and the inner chamber 2 is thus connected to the suction passage 11. The air valve 14 is closed. The suction valve 8 of the outer chamber 1 is closed and the air passage 18 to the outer chamber 1 is open. Consequently fuel will 40 flow through the fuel passage 27 and valve 29 into the inner chamber 2, while the outer chamber 1 can discharge through the valve 33. As the inner chamber 2 fills the float 45 22 rises and finally abuts against and lifts the bridge 19, together with the valves thereon, thereby reversing the operation of the suction chambers 1 and 2. The valve 9 closes and the valve 8 opens (Fig. 2) 50 whereby the inner chamber 2 becomes isolated from the suction passage and the outer chamber 1 becomes connected thereto. On the other hand the inner chamber 2 becomes connected through the valve 14 to the atmosphere, and the outer chamber 1 isolated 55 therefrom, by the slide valve 14 closing the channel 18.

As a consequence the discharge valve 32 of the inner chamber 2 opens and allows 60 the contents in this chamber to flow into the casing 34, and through the fuel conduit to the carburettor, while the outer chamber 1 fills with fuel which flows in through the passage 28 and valve 30.

65 A pressure compensation between the two

chambers 1 and 2 through the passages 27 and 28, is not possible, since the check valve 29 of the inner chamber 2 is held tight against its seat by the suction in the outer chamber 1. The fuel discharge valve 33 of the outer chamber 1 remains closed by the suction therein. On gradually discharging the inner chamber 2 the float 20 sinks and on striking against the flange 23 on the tube 20 the position of the suction and air valves 70 are reversed (Fig. 1).

The outer chamber 1 is now in turn subjected to atmospheric pressure and the inner chamber 2 to suction. The valve 33 opens while the valve 32 closes, the outer 80 chamber 1 discharges into the casing 34 and into the conduit to the carburettor, while the inner chamber 2 again fills. In this manner the cycle of operations is continuous.

Overflowing of the outer chamber 1 is prevented by the float 24, which would close the channel 12 by means of the valve 26 and thus prevent fuel from being drawn into the 90 passage 12.

What I claim is:

1. A liquid fuel supply device comprising an inner chamber; an outer chamber; a ring forming a cover for said outer chamber; a cover for said inner chamber secured to said ring; a double suction valve in said cover adapted to control the suction for both chambers; an air inlet valve in said cover adapted to control the supply of air into the chambers; a bridge member secured to 95 said valves; a float in said inner chamber adapted to actuate the valves by means of said bridge; a fuel inlet for each chamber; and a fuel outlet for each chamber.

2. A liquid fuel supply device for internal 105 combustion engines comprising two suction chambers arranged one within the other, an automatic fuel-inlet valve and an automatic fuel-outlet valve in each chamber, an air-inlet passage and a suction passage communicating with each chamber, valves in 110 said passages adapted to alternately open and close said passages to the said chambers, a connection between said valves, and a float in one of the chambers adapted in its raised 115 position to actuate said connection and valves whereby the chambers will in accordance with the position of the float be opened alternately to atmosphere and suction, substantially as set forth.

3. A liquid fuel supply device comprising an inner chamber; an outer chamber; a cover for said chambers; a suction valve in 125 said cover adapted to control the suction for said chambers; an air inlet valve in said cover adapted to control the supply of air into said chambers; a bridge member secured to said valves; and a float in one of said chambers adapted to actuate the valves by means of said bridge.

4. A liquid fuel supply device comprising an inner chamber; an outer chamber surrounding said inner chamber; a cover for said chambers; a float in said inner chamber; a suction valve in said cover for controlling the suction in said chambers; an air inlet valve in said cover for controlling the inlet of air in said chambers; a fuel inlet in said cover for each chamber; a fuel outlet for each chamber; and means operated by said float for operating both valves simultaneously to intermittently fill and empty said chambers of fuel.

5. A liquid fuel supply device comprising an inner chamber having a tube secured thereto; an outer chamber surrounding said inner chamber and having an outlet; a cover for said chambers; a float in one of said chambers; a pair of valves in said cover for controlling the inlet of air and suction in said chambers and operated by said float;

and a fuel outlet casing secured to the bottom of said outer casing and in communication with said tube and outlet, said tube extending through said outer chamber.

6. A liquid fuel supply device comprising an inner chamber; an outer chamber surrounding said inner chamber; a cover for said chambers; a fuel inlet for each chamber; a pair of valves in said cover for controlling the inlet of air and the suction in said chambers; a float in one of said chambers; and means secured to said valves and operated by said float for simultaneously operating said valves to intermittently fill and empty each chamber of fuel.

In testimony whereof I affix my signature in presence of two witnesses.

OTTO SIEFERT.
